UNITED STATES PATENT OFFICE.

BÉLA SCHAEFER, OF FRANKFORT-ON-THE-MAIN-BOCKENHEIM, GERMANY, ASSIGNOR
TO THE FIRM OF HARTMANN & BRAUN A. G., OF FRANKFORT-ON-THE-MAIN, GERMANY.

METAL-VAPOR RECTIFIER AND SIMILAR APPARATUS.

1,285,806.

Specification of Letters Patent. Patented Nov. 26, 1918.

Application filed July 23, 1912, Serial No. 711,082. Renewed April 19, 1918. Serial No. 229,657.

To all whom it may concern:

Be it known that I, BÉLA SCHAEFER, a citizen of the German Empire, and a resident of Frankfort-on-the-Main-Bockenheim, in the 5 Kingdom of Prussia, Province of Hesse-Nassau, Germany, have invented certain new and useful Improvements in Metal-Vapor Rectifiers and Similar Apparatus, of which the following is a full, clear, and exact 10 description.

This invention relates broadly to metallic vapor rectifiers and the like, and more particularly aims to provide an apparatus adapted efficiently to condense the generated 15 metallic vapors.

The cardinal object of this invention is to provide, in connection with the well-known vacuum chamber (hereinafter referred to as the main vessel), an externally 20 situated cooling or condensing chamber or chambers which, while of very simple construction, will exceed in efficiency anything heretofore proposed.

Another object is to so provide such a 25 condensing chamber that the condensed metallic vapor flows directly from the condensing chamber back to the main vessel; as opposed to the indirect backflow, induced by a Sprengel pump or other auxiliary device, 30 heretofore present in connection with the condensation of mercury vapor.

Another object is to provide a gas-tight 35 connection between the main vessel and a condensing chamber, and a connection which is preferably arranged for the convenient detachment of said condensing chamber from said main vessel.

Another object is to provide such a combination of main vessel and condensing 40 chamber as to permit of the convenient introduction within the main vessel of one or a plurality of anodes, either to extend laterally or to depend within said main vessel.

Other objects and aims of the invention, 45 more or less broad than those stated above, together with the advantages inherent, will be in part obvious and in part specifically referred to in the course of the following description of the elements, combinations, arrangements of parts and applications of 50 principles constituting the invention; and the scope of protection contemplated will appear from the claims.

Referring now to the accompanying drawing, which is to be taken as a part of this 5 specification, and wherein are shown several embodiments of this invention as at present preferred:

Figure 1 is a vertical sectional view, taken axially of one of said embodiments; 60

Fig. 2 is a similar view, taken axially of another of said embodiments; and

Fig. 3 is a similar view, taken axially of another of said embodiments.

Similar reference characters refer to similar parts throughout the several views of the 65 drawing.

Referring now particularly to Fig. 1, the actual vacuum vessel *g* is furnished with a plurality of anodes *a*₁ and *a*_n and with a 70 cathode *k*, and is sealed at its upper and lower extremities by means of covers *b* and *d*. The cover *d* thus here serves as a means for the introduction into the vessel *g* of the anodes, and as a joint between the chamber 75 *c* and said vessel. Attention is directed to the valuable annular space established between the chamber *c* and the vessel *g*, which may constitute a convenient cavity for the insertion, withdrawal or adjustment of said 80 anodes. The condensing chamber *c* communicates with the vessel *g* by way of the opening *o*, and is mounted upon and supported by said vessel *g* in the manner shown, that is, by means of the screws *f*. Both the 85 vessel *g* and the chamber *c* are preferably surrounded by jackets *k*₁ and *k*₂, which, by way of the tubes *r*₂, *r*₁ and *r*₃, here communicate with one another and are cooled by means of a flowing or circulating fluid. 90

Valves *m* and *n* enable the temperature to be regulated within wide ranges. It should be noted that the anodes are arranged as far removed from the center of the opening *o* as practicable to facilitate convenience in manipulating the screws *f* when connecting the main vessel *g* with the condensing chamber *c*.

The manner of operation of this embodiment, in respect of the incidental generation of metallic vapor, is in accordance with the usual method. In the present instance, however, the vapor ascends toward and passes through the opening *o* and thence into the large but immediately adjacent condensing chamber *c*, as diagrammatically in 100 105

dicated by the arrows; so that the metal condensed from the metallic vapor is enabled thereupon to descend, pass through the said opening σ , and return to mingle with the bed 5 of metal surrounding the cathode k , the same bed of metal from which metallic vapor was, or simultaneously is, being generated.

Referring now particularly to Fig. 2, it will be observed that the same shows a construction generally similar to that of Fig. 1, as may be observed from the similar reference numerals applied to both said figures, but a construction wherein the capacity of the condensing chamber c is considerably 15 larger than that of the vacuum vessel g and wherein the chamber c is provided with a plurality of baffle plates s which serve to increase the condensing surface and at the same time collect dust and prevent the same 20 from impairing the action of the vacuum pump.

It will be observed that the parts here constituting the main vessel g and the chamber c , both in the embodiment shown in Fig. 25 1 and in that shown in Fig. 2, are preferably of equal dimensions (excepting, and that only in the case of the embodiment shown in Fig. 2, merely as regards length), thus rendering the manufacture of the apparatus considerably simplified. It will also be observed that the connection between the two vessels offers the lowest resistance attainable to the passage of gas or vapor.

The manner of operation of this embodiment is generally similar to that described above in connection with the operation of the embodiment shown in Fig. 1.

Referring now particularly to Fig. 3, it will be observed that the same shows a construction generally similar to that of Fig. 1, as may be observed from the similar reference numerals applied to both said figures, but a construction wherein the condensing chamber c of either Fig. 1 or Fig. 2 is replaced by a coiled tube c and wherein the lower terminus of said tube c is detachably connected with the main vessel g as by means of the screw threads shown. It should be noted that it is preferable to have 50 the cooling surface presented by said tube c equal to or greater than the cooling surface presented by the main vessel g . Indeed, instead of a cylindrical chamber c , any system of tubes connected with a vacuum vessel g 55 may within the scope of this invention equivalently serve as a condensing apparatus; and inasmuch as the cooling effect depends only upon the total surface of the condensing chamber, this effect may within the 60 scope of this invention be further enhanced by arranging additional cooling walls within the main vessel or elsewhere within the apparatus.

The manner of operation of this embodiment is generally similar to that described

above in connection with the operation of the embodiment shown in Fig. 1.

It should be understood that in vapor electric apparatus and more particularly in mercury vapor rectifiers for small output, 70 the vacuum or main vessel (say the vessel g) is commonly made of glass and so fashioned that a considerable part of it serves for condensing the metal vapors; and that even in mercury rectifiers for large output, 75 wherein said vessel ordinarily consists of metal, a separate condensing chamber has not hitherto been provided, a relatively large vacuum or main vessel g (and an ample cooling of the vessel walls) having 80 been deemed sufficient. Experience has, however, shown that the cooling of the surface of the main vessel is not sufficient, and that to secure efficiency in a rectifier having a metal vessel, the provision of a separate 85 condensing chamber is necessary; and hence the present invention, which discloses an associated main vessel g and an independent, separate condensing chamber c . This independent condensing chamber, moreover, 90 is so arranged in such conveniently detachable relation to the main vessel, that there are provided, not only the advantages inherent in the assembled construction, but also the advantages resident in the fact that 95 the anodes may be introduced within the main vessel from overhead, rather than laterally, thus to dispense with the many defects usually encountered in lateral introduction. A cardinal defect in connection 100 with lateral introduction of the anodes (for example, through side branches welded into the vessel) would be due to the fact that the welded points cannot be rendered absolutely gas-tight. It would thus be seen that even 105 in the cases of heretofore known constructions the overhead introduction of the anodes is more favorable, since welding points could be avoided; but in vacuum vessels having no condensing chamber, and 110 especially in cylindrical vessels of this type, the facts have been that, on the one hand, in endeavoring to obtain the required capacity by enlarging the lateral dimensions, as the diameter, of the vessel, very large terminal pieces have been required, the anchoring and tightening of which offered many 115 difficulties, and, on the other hand, in endeavoring to obtain such capacity by enlarging the vessel longitudinally, leading-in conductors for the anodes of excessive length have been necessary, capable of conducting the heat only in a very insufficient manner.

While it is true that in some vacuum vessels, externally situated condensing chambers have been employed, it should be noted that these have been of such small dimensions in comparison with the main vessel that any material enlargement of the condensing surface has been practically impos- 130

sible; moreover, their construction has been complex and their manner of operation has been quite different from that which characterizes the present invention, in that not only was it necessary to condense the metal vapors, present in abundance, but to remove obnoxious gases and to recover any mercury which may have accidentally been drawn out. They have been provided with various means (such as a Sprengel's air-pump, magnesium arc, &c.) to remove extraneous gases which have penetrated into or were generated within the main vessel. And it was in the light of several inventions since come into existence, which are calculated to prevent the access of air, as well as to remove the residual gases and the necessity for as frequently as heretofore exhausting the air, that the present invention was conceived.

Therefore, in carrying this invention into practice, it is not sufficient to use an auxiliary vessel or chamber of relatively small internal capacity, but it is essential that by the addition of this chamber the original internal capacity of the apparatus shall be greatly increased and, preferably, at least doubled.

It will readily be seen that, in addition to the novel employment of an independent, separate condensing chamber as and of the character herein described, a disclosure is presented, due to the characteristic arrangement of the parts shown in connection with each of the various embodiments of this invention, that, among other advantageous features, permits of a new and increased efficiency of the apparatus, permits of the ready separation of the main vessel and condensing chamber (whether to insert or adjust the anodes or otherwise to have access to the interior of the main vessel), permits of a relatively narrow, normally gas-tight passageway (the opening *o*) between the main vessel and condensing chamber, and permits of an overhead rather than a lateral insertion or adjustment of said anodes at any time, either via annular space *s*, or simply separating, by means of the convenient arrangement shown, as, for example, the cover *d*, the main vessel and the condensing chamber.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the in-

vention which, as a matter of language, might be said to fall therebetween.

Having described my invention, what I claim as new and desire to secure by Letters Patent, is:

70

1. In metal-vapor electric apparatus, in combination, a vacuum chamber, an independent condensing chamber, one of said chambers being located above the other but spaced therefrom, a relatively narrow tube 75 connecting said chambers, and a plurality of anodes passing through the top and into the interior of the lower of said chambers, the outer ends of the anodes being accessible within the space between the two chambers. 80

2. In metal-vapor electric apparatus, in combination, a vacuum vessel, a removable cover for the same, anodes carried by the cover, and a condensing chamber supported by the cover and in communication with 85 the interior of the vacuum vessel.

3. In metal-vapor electric apparatus, in combination, a vacuum vessel, a cover for the same, anodes carried by the cover, and a condensing chamber supported by the cover 90 and in communication with the interior of the vacuum vessel, said cover and the condensing chamber being spaced apart.

4. In metal-vapor electric apparatus, in combination, a vacuum vessel and an independent condensing chamber having an internal capacity equal to or greater than that of the vacuum vessel, and means for detachably connecting the vacuum vessel and the condensing chamber together, said means 100 providing a restricted passage between them.

5. In metal-vapor electric apparatus, in combination, a vacuum vessel, an independent condensing chamber connected to the vacuum vessel by a relatively narrow passage, and a cooling jacket adjacent said vessel and said chamber. 105

6. In metal-vapor electric apparatus, in combination, a vacuum vessel including two chambers arranged one above the other, the upper one, at least as large as the lower one, serving as a condensing chamber, a cover for the lower vessel, anodes supported by said cover and extending into the lower vessel, the upper vessel having a bottom 110 spaced from said cover, and a restricted conduit establishing communication through the bottom of the upper chamber and the cover of the lower chamber.

7. In metal-vapor electric apparatus, in combination, a vacuum vessel and a condensing chamber in superposed relation, the bottom of one spaced apart from the top of the other, a plurality of anodes carried by the top of the vacuum vessel, and a conduit extending across the space between the bottom of the condensing chamber and the top of the vacuum vessel and establishing a communication between the interiors of the vacuum vessel and condensing chamber. 115 120 125 130

8. In metal-vapor electric apparatus, in combination, an upper condensing chamber, a lower vapor chamber, a cover for the vapor chamber having an orifice which communicates with the upper condensing chamber, said orifice being widened at its upper part so as to receive the lower extremity of the condensing chamber, the said cover being detachably connected with the vapor chamber, and a plurality of electrodes led in through said cover.

9. In metal-vapor electric apparatus, a vapor chamber, a condensing chamber in communication therewith, cooling jackets surrounding the vapor chamber and the con-

densing chamber, said jackets being in communication with each other.

10. In metal-vapor electric apparatus, in combination, a vapor chamber, a condensing chamber in communication therewith, a plurality of electrodes within the vapor chamber, and a screen for directing the anode streams toward the cathode.

In testimony whereof I have affixed my signature in presence of two witnesses.

BÉLA SCHAEFER.
